UNITED STATES PATENT OFFICE

SHOTARO TAKAOKA, OF GARDENA, CALIFORNIA

ELECTRIC CAUTERIZER

Application filed October 29, 1930. Serial No. 491,839.

This invention relates to an electrical device intended as a massage implement, and as a cauterizer and heat applicator to apply heat at any desired local part of the body.

5 The objects of the invention are, to provide means for applying heat to any part of the body for producing therapeutic effect, and to provide a curative and healing means for all ailments which are alleviated by application of heat, counterirritant, or cautery.

10 The object of the invention is to provide a device of this character whereby the application of the heat may be made on limited surfaces and points, as will be hereinafter set forth.

15 The drawing exhibits an embodiment of the invention which I have so far found to be the most practical in use, and wherein an electric heating grid is enclosed in a casing, 20 and the casing covered with heat insulating materials, except for the small exposed part of the casing serving as the heat applicator.

25 Various modifications may be made without departing from the spirit and nature of the invention, which consists in enclosing an electric heating grid of suitable proportions in a heat insulating jacket with a limited exposure of the heat applicator.

30 The device is particularly adapted for treatment of pus formations around the teeth, and similar ailments.

35 In the drawing, Figure 1 is a side elevation of the cauterizing device. Fig. 2 is a sectional elevation of the same. Fig. 3 is a detail view of the heating grid. Fig. 4 is a detail view of the heating grid turned 45°. Fig. 5 is a front elevation of the device with handle removed.

40 Referring to the drawing in detail, casing 11 is provided with handle 12, secured by screws 13. Casing 11 has an applicator projection 14, whereby heat may be applied. The casing has an inner cover 15, made preferably of asbestos or mineral wool, of non-absorbing material that prevents radiation of heat, or similar material. On the outer surface, I provide a jacket 16, of soft rubber, or similar suitable material. Within casing 11, I provide mica forms 17, 18, 19 and 45 20, serving to support a wire filament 21,

which is the heating grid. Wire 21 is soldered to terminals 22, of a double wire conductor 23, extending through handle 12.

In use, the wire conductor 23 is energized with an electric current, thereby energizing 55 the heating grid, which heats the applicator 14. The device is then applied to the part of the body to be treated, thereby applying heat, and producing therapeutic effects through the application of said heat and 60 through application of massage on moving the applicator.

65 From the foregoing description and drawing, it may be seen that I have provided simple and efficient elements for application of heat to the human body in the treatment of disease or relief of various ailments, and whereby such application may be made at particular points and to limited areas of the body. 70

It may be noted that all external surfaces of the applicator likely to come in contact with the body, are well rounded.

I claim:

1. In an electric cauterizer, a casing including an applicator forming the upper extremity thereof, an electric grid within the casing arranged for heating the active surface of the applicator, a handle for the casing, and heat-insulating jackets enclosing 80 the casing with the applicator projecting therefrom. 75

2. In an electric cauterizer, a casing including an applicator projecting angularly from the upper end thereof, an electric grid within the casing, a handle for the casing, and heat-insulating jackets enclosing the casing with the applicator projecting therefrom. 85

3. In an electric cauterizer, the combination with a casing, an applicator extremity integral therewith, heat-insulating jackets covering the non-active surface of the casing, an electric heating grid within the casing and in operative relation to the active surface of the applicator. 90

95 In testimony whereof, I hereunto affix my signature.

SHOTARO TAKAOKA.
